UNITED STATES PATENT OFFICE.

GUSTAVE R. THOMPSON, OF NEW YORK, N. Y., ASSIGNOR TO E. W. BLISS COMPANY, OF BROOKLYN, NEW YORK, A CORPORATION OF WEST VIRGINIA.

DRAWING PRESS.

Application filed March 22, 1923. Serial No. 626,849.

To all whom it may concern:

Be it known that I, GUSTAVE R. THOMPSON, a citizen of the United States of America, residing in the borough of Richmond, city and State of New York, have invented certain new and useful Improvements in Drawing Presses, of which the following is a specification.

This invention relates to improvements in drawing presses and aims to provide improvements therein.

The invention provides a drawing press of simple and compact construction, of the type in which the means for driving the punch slide and blank-holder or die slide distributes the force symmetrically to said slides, in a manner especially suitable for presses having a considerable span, or distance between uprights. The invention further provides a press in which the overall height and longitudinal and transverse width of the press may be of minimum dimensions for a given stroke and width between uprights, or span. It further provides a press in which the working parts of the blank-holder or die slide driving mechanism are substantially confined to the middle portion of the upper part of the press frame.

An embodiment of the invention is illustrated in the accompanying drawings, in which—

Figure 1 is a front view of a press, with parts broken away to more clearly show the construction.

Fig. 2 is a top plan view, and

Fig. 3 is a view partly in vertical section and partly in side elevation.

Referring to said drawings, numeral 10 designates the press frame, having uprights 11, 12 spaced widely apart, a bed 13, and a crown 14, the crown and bed being tied together, as usual, by tie rods 15, at each side of the press. Between the side frames 11, 12 is a slide 20 adapted to carry a blank-holder or die, the bed 13 being adapted to carry a complementary tool between which tools on the bed 13 and slide 20 a sheet metal blank is adapted to be gripped.

A second slide 25 guided in the slide 20, as indicated at 26, and adapted to carry a punch, is provided. The punch slide 25 is conveniently driven by pitmen rods 27, 28 symmetrically connected to said slide, and to cranks 30, 31 on a crank-shaft 33 extending lengthwise of the press, and having driving

wheels or gears 34, 35, at the ends thereof, which are driven with equal force by pinions 37, 38, on a fast moving back-shaft 39.

Means are provided for driving the blank-holder or die slide 20 with a dwell in its movement, as usual in this type of press. These means comprise an actuating part 41 on the crown 14 between the uprights, and separate connections 43, 44 from said actuating part 41 on each side of a plane intersecting the axis of said crank-shaft 33, to said blank-holder slide 41. The actuating part 41 is conveniently in the form of a slide midway of the crown 14, and working in guides 46 in said crown, and the separate connections 43, 44 are preferably in the form of two or more rocking parts 48, 48', 49, 49', connected by links 51, 51' to said slide 41, by links 53, 53' to one another, and by links 55, 55' to said slide 20. The rocking parts 48, 48' are preferably in the form of rock-shafts 57 having single arms 58, 59 thereon and turning in a hollow portion 60 of the crown 14, a single link 51, 51' connecting each arm 58 to the actuating slide 41. The rocking parts 49, 49' are also preferably in the form of rock-shafts 63 each having one intermediate arm 64, and two extreme arms 65, 66 thereon, the intermediate arms 64 being in the hollow portion 60 of the crown, and connected to the arm 59, by single links 53, 53', and the extreme arms 65, 66 are preferably located at the outer sides of the crown 14, and each arm 65, 66 and a link 55, 55' constituting a toggle 70. The arms 59 and each of the links 53, 53' may also if desired be made so as to constitute toggles. At the time the parts of the toggle 70 are in substantial alignment the links 51, 51' are moving through an arc which is substantially perpendicular to the axes of said links, thereby imparting a minimum of movement to said links and the rocking parts 48, 48' connected thereto, and the dwell of 90° and over usual in this type of press is due to the joint action of the toggles and links, as just explained.

The actuating slide 41 is conveniently connected to a crank 75 on the crank-shaft 33 by means of a link or connecting rod 77, 105 and the crank 75 is given the usual lead of 45° over the cranks 30, 31 (figured from the dead-center line of said cranks 30, 31), whereby the dwell of the blank-holder slide 20 is timed so as to occur while the cranks 110

30, 31 connected to the punch slide 25 are moving through 90° preceding the limit of throw of the said cranks (i. e., the working part of the working stroke).

5 The axes of the rocking parts 49, 49', 48, 48' may lie in substantially the same horizontal plane, and all parts of the connections 43, 44 may lie within the dimensions of the side frames and crown.

10 The inventive ideas may receive other embodiments than that herein specifically illustrated and described.

What is claimed is:

1. A drawing press comprising a crank-shaft, a blank-holder or die slide, and means for operating said blank-holder or die slide, said means comprising rocking parts at each side of the press turning on axes transverse of said crank-shaft, toggles between said rocking parts and said blank-holder slide, 15 a second rocking part nearer the middle of the press turning on an axis parallel with those of said first-named rocking parts, connections between said first and second-named rocking parts for transmitting movement from the latter to the former, and means connected to an intermediate part of said crank-shaft for rocking said second rocking part.

30 2. A drawing press comprising a crank-shaft, a blank-holder or die slide, and means for operating said blank-holder or die slide, said means comprising rocking parts at each side of the press turning on axes transverse of said crank-shaft, toggles between said rocking parts and said blank-holder slide, a second rocking part, connections between said first and second rocking parts, and means connected to an intermediate part of said crank-shaft for rocking said second rocking part, said first and second rocking parts having their axes in substantially the same horizontal plane.

35 3. A drawing press comprising a crank-shaft, a blank-holder or die slide, and means for operating said blank-holder or die slide, said means comprising rocking parts at each side of the press turning on axes transverse of said crank-shaft, toggles between said rocking parts and said blank-holder slide, a second rocking part, connections between said first and second rocking parts, and means connected to an intermediate part of said crank-shaft for rocking said second rocking part, said first rocking parts being in the form of short rock-shafts having toggle arms at each end thereof.

40 4. A drawing press comprising a crank-shaft, a blank-holder or die slide, and means for operating said blank-holder or die slide, said means comprising rocking parts at each side of the press turning on axes transverse of said crank-shaft, toggles between said rocking parts and said blank-holder slide, a second rocking part, a single connection be-

tween each of said first rocking parts and said second rocking part, and means connected to an intermediate part of said crank-shaft for rocking said second rocking part, said first rocking parts being in the 70 form of short rock-shafts having toggle arms at each end thereof.

5. A drawing press comprising a crank-shaft, a blank-holder or die slide, and means for operating said blank-holder or die slide, 75 said means comprising rocking parts at each side of the press turning on axes transverse of said crank-shaft, toggles between said rocking parts and said blank-holder slide, second rocking parts, a single connection 80 between each of said first named rocking parts and said second rocking parts, and means connected to an intermediate part of said crank-shaft for rocking said second rocking part, said first rocking parts being in the form of short rock-shafts having toggle arms at each end thereof and said connections between said rock-shafts and said second rocking parts being single, and said means for rocking said second rocking 85 parts comprising a single connection to each of said second rocking parts.

6. A drawing press comprising a crank-shaft, a blank-holder or die slide, and means for operating said blank-holder or die slide, 90 said means comprising rocking parts at each side of the press turning on axes transverse of said crank-shaft, toggles between said rocking parts and said blank-holder slide, second rocking parts in connection with each 100 of said first named rocking parts, connections between said first and second rocking parts, and means connected to an intermediate part of said crank-shaft for rocking said second rocking part, said means for rocking said second rocking parts comprising a slide, and connections between said slide and each of said second rocking parts.

7. A drawing press comprising a crank-shaft, a blank-holder or die slide, and means for operating said blank-holder or die slide, said means comprising an actuating slide and connections to an intermediate part of said crank-shaft, and separate connections at each side of the mid-plane of the press intersecting the axis of said crank-shaft, between said actuating slide and said blank-holder or die slide.

8. A drawing press having a blank-holder, 110 a crank-shaft, and blank-holder operating mechanism comprising toggles, rocking parts at each side of the press operating said toggles, turning on axes transverse of the crank shaft axis, an intermediate moving part, a driving connection thereto from the middle part of the crank-shaft, and operative connections from said moving part extending horizontally to the respective rocking parts for straightening said toggles.

9. A drawing press having a blank-holder,

a crank-shaft, and blank-holder operating mechanism comprising short rock-shafts above the crank-shaft on axes transverse thereto, having end arms, toggles including said arms for engaging the blank-holder, horizontal links connecting them to said

rock shafts, and driving connections from the middle of the crank-shaft to said rocking parts.

10

In witness whereof, I have hereunto signed my name.

GUSTAVE R. THOMPSON.
